UNITED STATES PATENT OFFICE.

THOMAS H. FERGUSON, OF PORTLAND, OREGON.

FLUID-FUEL-REGULATING SYSTEM.

1,243,396.

Specification of Letters Patent.

Patented Oct. 16, 1917.

Application filed February 7, 1914. Serial No. 817,248.

To all whom it may concern:

Be it known that I, THOMAS H. FERGUSON, a citizen of the United States, residing at Portland, in the county of Multnomah and State of Oregon, have invented certain new and useful Improvement in Fluid-Fuel-Regulating Systems, of which the following is a specification.

My invention relates to fuel control apparatus for furnaces adapted to the consumption of liquid fuel, and has for its object the economization of fuel through means employed for automatically regulating the combustion. My invention is applicable to furnaces heated by a liquid fuel or oil burner in which the fuel is fed by steam generated by the furnace, and it comprehends novel means for regulating the draft of the furnace, the flow of oil, and the supply of steam relatively to the operative requirements of the apparatus, and all looking toward uniformity of combustion and, in consequence thereof, toward economy of operation.

What constitutes my invention will be hereinafter specified in detail and succinctly set forth in the appended claims.

In the accompanying drawings:

Figure 1 is a front elevation of a furnace and boiler equipped with a preferred form of embodiment of my invention.

Fig. 2 is a side elevation, partially in section, of my steam and oil regulator, directed particularly to illustration in detail of the steam-actuated damper, control mechanism.

Fig. 3 is a vertical section, partially in elevation, of my steam and oil regulator proper.

Referring to the characters on the drawings, 50 indicates a built-in furnace, provided with usual draft doors 51 and a flue 47. The presence of a boiler is indicated by the numeral 41, and a damper 42 having a counterweight 44 is shown as provided within the flue 47. The parts above described may be of any usual or preferred type, construction and dimensions. Coming now to consideration of instrumentalities more directly involved in my invention, 51 indicates the main steam shell of my regulator. To its upper end, preferably, is threaded an oil valve shell 2, and to its lower end, preferably, is united, as by similar means, the crown 5, of a diaphragm case whose lower part is indicated by the numeral 25. A crown of bolts 5^a uniting the

parts 5 and 25 secures between them a flexible diaphragm 24 which operatively divides the diaphragm case. Upon its lower side the diaphragm 24 is supported by a spring 27 seated in a reinforcing cup or plate 26 disposed against the diaphragm and a cup 29 adjacent to the end of the case-member 25 which carries coaxially an adjustment screw 32. A guide core 28 extends from the plate 26 through the spring 27 to limit the adjustment of the cup 29 which is recessed for the reception of the lower end of the core. Apertures 30 and 31 with cup 29 and case-member 25, respectively, provide constant atmospheric pressure within the member 25, or, in other words, upon the spring-engaging side of the diaphragm 24.

Above said diaphragm a nut 33 abutting against a washer 34 is threaded to a reduced end of the core 28 which penetrates the diaphragm and unites the core and parts appurtenant thereto. 10 indicates a valve stem which, at its lower end, screws into the empty upper end of the nut 33 and is secured by a lock nut 22. Passing with a piston-fit through the bottom of shell 1, the stem 10 extends to a ball valve 8 within the shell 2 and is connected thereto. 9 indicates the valve seating part for the valve 8 and establishes communication between compartments *a* and *b* of the shell 2. A pipe 6 united to the shell 2, as indicated at 7, makes communication between the compartment *a* and a source of liquid fuel supply, preferably under pressure, not illustrated. A pipe 11 is adapted to deliver the liquid fuel from compartment *b* of the shell 2 after it passes the valve 8 to any burner adapted for its combustion and not illustrated but assumed to be in proximity, operative for heating purposes, to the boiler 41. The stem 10 in passing through the shell 2 below the compartment *b* makes a steam-tight fit so as to shut off communication between the respective contents of the shells 1 and 2.

A partition wall *c* divides the interior of the shell 1 into two chambers *d* and *e*, the former communicating through a steam supply pipe 13 with the boiler 41, and the latter making through a steam delivery pipe 17, operative communication with the illustrated burner above referred to as being connected likewise with the pipe 11.

The partition *c* is perforated by a valve 110 seating port 18 which is controlled by a valve 16, secured, as by a nut 15, to the stem

10. The disposition of the respective valves 8 and 16 upon their common stem 10 is such as to provide, through reciprocation of the stem, for the simultaneous opening and closing of the ports 9 and 18, respectively, and thereby a simultaneous supply of fuel and steam to the respective pipes 11 and 17, whose relative size may be made the means contemplated for regulating the relative 10 quantities of the supply of each. The chamber *d* is in operative communication with the diaphragm 24, as through a steam duct 23, in the bottom of the shell 1.

12 indicates a recording steam gage or 15 register which, being well known in the art as a means of recording fluid pressures, may be of any preferred type and is unnecessary to describe herein.

The above described mechanism constitutes 20 apparatus for the automatic regulation, in the manner hereinafter described, of steam and fuel supply with economic results and is in so far completion itself, but I prefer to simplify those results by the incorporation 25 with the steam regulation of means for controlling the damper 42, whereby the generation of steam is affected at its source.

Accordingly I provide the shell 1 with a branch 14 which terminates in the upper 30 half of a regulator shell 3, with which a lower half 4 is united to confine between them a flexible diaphragm 19. A plunger 37 is operatively united to the diaphragm 19, as by a button plate 20, upon the reduced 35 end of the rod and a nut 21 threaded thereto. The plunger 37 is transversely penetrated by a bearing aperture 40 whose opposite sides engage a lever 35 that is pivoted, as indicated at 38, between lugs 39 40 located upon opposite sides of a transverse opening in the tail-piece 36 of the part 4.

The lever 35 extending from its pivotal point 38 through the opening in the tail-piece accommodates an adjustable collar 46 45 by which hinge connection is made at its lower end with a rod 45 whose upper end is, in a like manner, connected with a crank arm 43 of the damper 42.

The operation of my apparatus may be 50 understood from the following description. Liquid fuel or oil is freely admitted through the pipe 6 to the compartment *a* whence it flows into compartment *b* and thence through pipe 11 for consumption, if the 55 valve 8 be open. Likewise steam from boiler 41 through pipe 13 enters chamber *d* and thence passing to chamber *c*, if the valve 16 be open, issues through pipe 17 and is led away, to service in conjunction with the oil 60 supplied through pipe 11. The pipes 6 and 13 and 11 and 17 being properly proportioned as to size, and the movement of the valves 8 and 16 being, as has been specified, 65 dependent upon that of a common stem 10, a flow of steam and oil in due proportions

is derived from the pipes 17 and 11, respectively.

Steam pressure from the chamber *d* entering through the duct 23 above the diaphragm 24 tends to close the valves 8 and 16. By the aid of the adjustment screw 32 the spring 27 may be set to the desired resistance to counterbalance the steam pressure upon the side of the diaphragm opposite the spring 27. In this way, by balancing the steam pressure against the spring pressure the pressure of steam necessary to close the valves may be determined and prescribed. Consequently the combustion supported from the contents of pipes 11 and 17 80 may be kept automatically regulated and the steam pressure in the boiler maintained at substantial uniformity.

A further check upon steam generation 85 may be imposed by operation of the damper 42, and I, therefore, contemplate the use of the auxiliary regulator embodying the diaphragm 19 for that purpose. Steam pressure in the chamber 3 is normally maintained a considerable extent below the pressure 90 in the boiler or on the diaphragm 24, due to the point of its communication with the regulator casing above the valve 16; but upon the opening of said valve, due to a falling off of the steam pressure in the 95 boiler, the pressure in the chamber 3 increases and the diaphragm is depressed to drive the plunger 40 outwardly. This communicates motion to the lever 35, which, in turn, through the rod 45, tends to open the 100 damper 42. The effect is to increase the draft of the flue 47 preparatory to an increase of heat under the boiler 41. As the pressure increases in pipe 13 pressure will also increase on diaphragm 24, thereby pulling down valves 8 and 16. As the valves 8 and 16 are closing, pressure is then decreasing on diaphragm 19, thereby allowing the balance weight 44 to fall back and close the 110 damper 42, which controls the heat in flue 47, keeping the hot gases from escaping to the atmosphere, as in common practice, and retaining them in the furnace, thus resulting in a great saving of fuel.

Through an aperture 25^a in the case 25 115 extends a lever 53, which is pivotally supported upon the pin 54 in the casing. From the inner arm of said lever rises a terminal portion 55 which bears against plate 26 resting against the diaphragm 24.

The outer arm is connected upon the pivot pin 53^a with the vertical bar or pointer 52, which rises to the registering gage 12, and by reason of the rising and falling of the diaphragm 24, due to variations in pressure thereon, the pointer will register on the chart the amount of opening in parts 9 and 18, and thereby indicate the amount of oil being consumed.

In the operation of my device it will be 130

apparent that the fuel supply may be fed by gravity, or pressure, as well as by steam. Steam passing through the port 18 and on to the burner is necessarily reduced in pressure where it enters the pipe 14 and is controlled by the position of the valve 16.

The pressure of the steam below the valve 16 and the oil above the ball valve makes a balanced construction which is easily operated by the diaphragm and readily responsive to slight fluctuations in the pressure of the steam. The damper is well balanced and a slight movement of its controlling diaphragm 19 results in a considerable movement of the same. By using a reduced pressure to operate the diaphragm 19 I am assured of sufficient pressure, even when the boiler pressure is low, to effect the desired results. The supply of steam pressure to said diaphragm 19 is dependent upon the pressure of the steam passing directly to the burner, and thus the movements of the damper will be in exact accordance with the requirements of the flame.

It will be understood, of course, by one skilled in the art, that upon proper adjustment of the screw 32, in the first place, the variations of steam pressure and consequent movements of the valve stem 10 will be slight and vibratory or of momentary duration. I prefer for that reason, among others, to employ the recording gage 12 whose record will indicate the variations of steam pressure, and serve as a guide to an operator in making any re-adjustment of the screw 32 in order to secure the best results in operation.

Having thus described my invention what I claim and desire to secure by Letters Patent is—

1. The combination with a boiler and a burner for the same, of a fluid fuel regulating system, comprising a steam pressure operated diaphragm, a spindle on one side of the diaphragm, separate oil and steam inlet chambers, and a beveled seated valve for controlling each of said chambers operated by the spindle, said steam inlet being below its valve and the oil inlet above its valve, whereby the pressure of the oil and steam acts upon opposite faces of the valves to effect a counterbalance.

2. The combination with a boiler and a burner therefor, of a fluid fuel regulator comprising a steam pressure operated diaphragm, separate oil and steam inlet chambers, a spindle on one side of said diaphragm passing through said chambers, bevel-seated valves operated by said spindle for controlling the passageways through said chambers, and separate steam and oil outlet chambers intermediate the inlet chambers, said steam and oil inlet chambers being positioned at the outer sides of their respective valves, whereby the steam and oil enter the

regulator in opposite directions and act upon the faces of their respective valves to effect a counterbalance.

3. The combination with a boiler and a burner therefor, of a fluid fuel regulator comprising a steam pressure operated diaphragm in communication with the boiler, separate oil and steam inlet chambers, a spindle on one side of said diaphragm passing through said chambers, valves operated by said spindle for controlling the passageways through said chambers, separate steam and oil outlet chambers intermediate the inlet chambers and communicating with the burner, an auxiliary flexible diaphragm operated by steam pressure supplied solely by the steam outlet chamber of said regulator, and a draft device controlled by said auxiliary diaphragm.

4. The combination with a boiler and a burner therefor, of a fluid fuel regulating system comprising a casing, a steam pressure operated diaphragm therein in communication with the boiler, a steam inlet for said casing also in communication with the boiler, a steam outlet for the casing in direct communication with the burner, a valve between said inlet and outlet chambers operated by the diaphragm to control the passage of steam therethrough whereby the valve is closed when the steam pressure in the boiler is high and opened when said pressure is low, and a supplementary flexible diaphragm and casing for controlling the operation of a damper adjacent to the burner, said casing having communication with said steam outlet chamber for supplying steam under pressure to operate said supplementary diaphragm, whereby the opening and closing of the damper is made dependent upon the pressure of steam in the burner.

5. The combination with a boiler and a burner therefor, of a fluid fuel regulator, comprising a steam pressure operated diaphragm, separate steam and oil passageways leading to the burner, and a beveled seated valve in each of said passageways controlled by said diaphragm for regulating the admission of oil and steam to the burner in accordance with the variations in the pressure of steam in the boiler, said valves being so arranged as to receive the pressure of the steam and oil from opposite directions to effect a counterbalance of the forces when operation of the valves are in closed position, and each of said valves being of equal area on its opposite faces, whereby they are independently balanced when in open position.

6. The combination with a boiler and a fuel burner therefor, means for supplying an admixture of steam and oil to said burner in regulated quantities in accordance with the pressure demands of the boiler, a draft

device for said burner, and means controlled by steam pressure from said burner to actuate said draft device.

7. The combination with a boiler and a liquid hydrocarbon fuel burner therefor, fuel supply means for said burner, means for supplying steam from the boiler to said burner to mix with the fuel, means regulated by boiler pressure for controlling the passage of steam and oil into said burner so that when the boiler pressure is high the passage of

steam and oil is cut off and when the boiler pressure is low the steam and oil are admitted to the burner, and means controlled by the regulated and reduced steam pressure in 15 the burner to actuate a draft device therefor.

In testimony whereof I affix my signature in the presence of two witnesses.

THOMAS H. FERGUSON.
